Primary Examiner — Deanna L Pratt(74) *Attorney, Agent, or Firm* — Klintworth & Rozenblat IP LLC(57) **CLAIM**

The ornamental design for a passenger information module with payment screen of graphical user interface, as shown and described.

DESCRIPTION

FIG. 1 is a perspective view of the passenger information module in which the payment screen of the claimed design is embodied; and,

FIG. 2 is a front view of the payment split screen of the claimed design.

The dashed lines in FIG. 1 show the environment, and form no part of the claimed design. The dashed lines in FIG. 2 illustrate portions of the payment screen which form no part of the claimed design.
